(57) **CLAIM**

We claim the ornamental design for a contour armrest, as shown and described.

DESCRIPTION

FIG. 1 is a top perspective view of a contour armrest, according to one embodiment;

FIG. 2 is a right side view of a contour armrest of FIG. 1, the left side view is a mirror image of the right side view of FIG. 2;

FIG. 3 is a front view of a contour armrest of FIG. 1;

FIG. 4 is a rear view of a contour armrest of FIG. 1;

FIG. 5 is a top view of a contour armrest of FIG. 1;

FIG. 6 is a bottom view of a contour armrest of FIG. 1;

FIG. 7 is a top perspective view of a contour armrest, according to a second embodiment;

FIG. 8 is a right side view of a contour armrest of FIG. 7, the left side view is a mirror image of the right side view of FIG. 8;

FIG. 9 is a front view of a contour armrest of FIG. 7;

FIG. 10 is a rear view of a contour armrest of FIG. 7;

FIG. 11 is a top view of a contour armrest of FIG. 7; and,

FIG. 12 is a bottom view of a contour armrest of FIG. 7.

The dashed lines are for purposes of illustrating environmental structure and form no part of the claimed design.
